(57) **CLAIM**

The ornamental design for a display panel or screen with an animated graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a display panel or screen with a first image of an animated graphical user interface showing my new design;

FIG. 2 is a front view of a second image thereof; and

FIG. 3 is a front view of a third image thereof.

FIG. 4 is a front view of a second embodiment of a display panel or screen with a first image of an animated graphical user interface showing my new design;

FIG. 5 is a front view of a second image thereof; and

FIG. 6 is a front view of a third image thereof.

FIG. 7 is a front view of a third embodiment of a display panel or screen with a first image of an animated graphical user interface showing my new design;

FIG. 8 is a front view of a second image thereof; and

FIG. 9 is a front view of a third image thereof.

FIG. 10 is a front view of a fourth embodiment of a display panel or screen with a first image of an animated graphical user interface showing my new design;

FIG. 11 is a front view of a second image thereof; and

FIG. 12 is a front view of a third image thereof.

FIG. 13 is a fifth embodiment of a display panel or screen with a first image of an animated graphical user interface showing my new design;

FIG. 14 is a front view of a second image thereof; and

FIG. 15 is a front view of a third image thereof.

FIG. 16 is a sixth embodiment of a display panel or screen with a first image of an animated graphical user interface showing my new design;

FIG. 17 is a front view of a second image thereof; and

FIG. 18 is a front view of a third image thereof.

FIG. 19 is a front view of a seventh embodiment of a display panel or screen with a first image of an animated graphical user interface showing my new design;

FIG. 20 is a front view of a second image thereof; and

FIG. 21 is a front view of a third image thereof.

FIG. 22 is an eighth embodiment of a display panel or screen with a first image of an animated graphical user interface showing my new design;

FIG. 23 is a front view of a second image thereof; and

FIG. 24 is a front view of a third image thereof.

FIG. 25 is a ninth embodiment of a display panel or screen with a first image of an animated graphical user interface showing my new design;

FIG. 26 is a front view of a second image thereof; and

FIG. 27 is a front view of a third image thereof.

FIG. 28 is a front view of a tenth embodiment of a display panel or screen with a first image of an animated graphical user interface showing my new design;

FIG. 29 is a front view of a second image thereof; and

FIG. 30 is a front view of a third image thereof.

FIG. 31 is an eleventh embodiment of a display panel or screen with a first image of an animated graphical user interface showing my new design;

FIG. 32 is a front view of a second image thereof; and

FIG. 33 is a front view of a third image thereof.

FIG. 34 is a twelfth embodiment of a display panel or screen with a first image of an animated graphical user interface showing my new design;

FIG. 35 is a front view of a second image thereof; and

FIG. 36 is a front view of a third image thereof.

FIG. 37 is a front view of a thirteenth embodiment of a display panel or screen with a first image of an animated graphical user interface showing my new design;

FIG. 38 is a front view of a second image thereof; and

FIG. 39 is a front view of a third image thereof.

FIG. 40 is a fourteenth embodiment of a display panel or screen with a first image of an animated graphical user interface showing my new design;

FIG. 41 is a front view of a second image thereof; and

FIG. 42 is a front view of a third image thereof.

FIG. 43 is a fifteenth embodiment of a display panel or screen with a first image of an animated graphical user interface showing my new design;

FIG. 44 is a front view of a second image thereof; and

FIG. 45 is a front view of a third image thereof.

FIG. 46 is a front view of a sixteenth embodiment of a display panel or screen with a first image of an animated graphical user interface showing my new design;

FIG. 47 is a front view of a second image thereof; and

FIG. 48 is a front view of a third image thereof.

FIG. 49 is a seventeenth embodiment of a display panel or screen with a first image of an animated graphical user interface showing my new design;

FIG. 50 is a front view of a second image thereof; and

FIG. 51 is a front view of a third image thereof.

FIG. 52 is a eighteenth embodiment of a display panel or screen with a first image of an animated graphical user interface showing my new design;

FIG. 53 is a front view of a second image thereof; and

FIG. 54 is a front view of a third image thereof.

FIG. 55 is a front view of a nineteenth embodiment of a display screen panel or with a first image of an animated graphical user interface showing my new design;

FIG. 56 is a front view of a second image thereof; and

FIG. 57 is a front view of a third image thereof.

FIG. 58 is a twentieth embodiment of a display panel or screen with a first image of an animated graphical user interface showing my new design;

FIG. 59 is a front view of a second image thereof; and

FIG. 60 is a front view of a third image thereof.

FIG. 61 is a twenty-first embodiment of a display panel or screen with a first image of an animated graphical user interface showing my new design;

FIG. 62 is a front view of a second image thereof; and

FIG. 63 is a front view of a third image thereof.

FIG. 64 is a front view of a twenty-second embodiment of a display panel or screen with a first image of an animated graphical user interface showing my new design;

FIG. 65 is a front view of a second image thereof; and

FIG. 66 is a front view of a third image thereof.

FIG. 67 is a twenty-third embodiment of a display panel or screen with a first image of an animated graphical user interface showing my new design;

FIG. 68 is a front view of a second image thereof; and

FIG. 69 is a front view of a third image thereof.

FIG. 70 is a twenty-fourth embodiment of a display panel or screen with a first image of an animated graphical user interface showing my new design;

FIG. 71 is a front view of a second image thereof; and

FIG. 72 is a front view of a third image thereof.

FIG. 73 is a front view of a twenty-fifth embodiment of a display panel or screen with a first image of an animated graphical user interface showing my new design;

FIG. 74 is a front view of a second image thereof; and

FIG. 153 is a front view of a third image thereof. The appearance of the image transitions from one of the images to another one of the images shown in FIGS. 1-3, FIGS. 4-6, FIGS. 7-9, FIGS. 10-12, FIGS. 13-15, FIGS. 16-18, FIGS. 19-21, FIGS. 22-24, FIGS. 25-27, FIGS. 28-30, FIGS. 31-33, FIGS. 34-36, FIGS. 37-39, FIGS. 40-42, FIGS. 43-45, FIGS. 46-48, FIGS. 49-51, FIGS. 52-54, FIGS. 55-57, FIGS. 58-60, FIGS. 61-63, FIGS. 64-66, FIGS. 67-69, FIGS. 70-72, FIGS. 73-75, FIGS. 76-78, FIGS. 79-81, FIGS. 82-84, FIGS. 85-87, FIGS. 88-90, FIGS. 91-93, FIGS. 94-96, FIGS. 97-99, FIGS. 100-102, FIGS. 103-105, FIGS. 106-108, FIGS. 109-111, FIGS. 112-114, FIGS. 115-117, FIGS. 118-120, FIGS. 121-123, FIGS. 124-126, FIGS. 127-129, FIGS. 130-132, FIGS. 133-135, FIGS. 136-138, FIGS. 139-141, FIGS. 142-144, FIGS. 145-147, FIGS. 148-150 and FIGS. 151-153, respectively.

The process or period in which an image transitions to another forms no part of the claimed design.

The outermost broken line illustrates a display panel or screen and forms no part of the claimed design. The remaining broken lines, illustrating portions of the graphical user interface, form no part of the claimed design.
